UNITED STATES PATENT OFFICE.

THOMAS E. ADAMS, OF CLEVELAND, OHIO.

COMMUTATOR FOR DYNAMO-ELECTRIC MACHINES.

SPECIFICATION forming part of Letters Patent No. 340,537, dated April 27, 1886.

Application filed December 5, 1885. Serial No. 184,824. (No model.)

To all whom it may concern:

Be it known that I, THOMAS EDGAR ADAMS, of Cleveland, Cuyahoga county, Ohio, have invented certain Improvements in Commutators of Dynamo-Electric Machines, of which the following is a specification.

My invention relates more particularly to that kind of commutator of which the Brush commutator is a type, in which the segments are so arranged that the several bobbins of the armature to which they are connected are cut out of electrical connection with the remainder of the circuit during a portion of each revolution.

15 The object of my invention is to provide a cutting-out segment or insulating-piece between the metal segments of a commutator which will have a higher resistance to the passage of the current from one metal segment to the others than those now in use, and also by reason of its anti-friction qualities to reduce the tendency to "cutting" between the contact-brushes and the commutator.

20 In the accompanying drawings, Figure 1 is a plan view of a commutator having my improved cut-out segments. Fig. 2 is an end view of the same. Fig. 3 shows a detached segment in perspective. Figs. 4 and 5 show in side and top views a modified form of the invention.

25 For illustration, the Brush commutator is chosen as a form well known; but I do not limit myself to any particular form of commutator.

30 A A represent my improved segments. They are preferably made of lignum-vitæ, though knots of deciduous trees and some other kinds of very hard and gummy woods are suitable.

35 The segments may be made of any suitable size or shape; but they should be provided with one or more V-shaped grooves, a a, cut diagonally across their wearing-surface, to prevent the production of a continuous plated surface from particles of metal lodging on the segment. The grooves are cut diagonally, to prevent pounding of the contact-brushes as they pass over them. They are V-shaped in cross-section, to enable the centrifugal force 40 to throw out any particles that may lodge in them. For durability and uniformity of wear,

the segments should have the end grain of the wood on their wearing-surface.

55 The advantage of using wood instead of metal for these segments is twofold. The primary advantage is the insulating property of the wood. The secondary advantage is its tendency to prevent cutting between the contact-brushes and the commutator. This tendency is due not only to the exudation of gum 60 from the wood, which acts as a lubricant, but by offering the friction of a different substance to the wearing-points of the brushes the continuous lines of friction are broken up, as the wood and copper segments alternate. The 65 V-grooves possess the further advantage of interposing so many air-spaces for the spark to bridge. By making the grooves of the proper size and number the wear of these segments may be made uniform with the rest 70 of the commutator.

75 To prevent charring on the end of the wooden segments, I provide refractory tips c, which may be of metal or of some vitreous material. Should the anti-friction qualities of this detachable cut-out segment be dispensed with, it may be made of any insulating material, and upon its wearing-surface have attached narrow pieces of metal, rawhide, or other substance capable of resisting wear, and having 80 interstices or grooves between them, to prevent particles of metal from making a continuous path and allowing the current to pass. This form is illustrated in Figs. 4 and 5, in which A is the insulating-block, and a a the 85 wearing-strips.

These detachable segments may be easily secured to the body of the commutator by screws c c.

Having thus described my invention, what I claim as new is—

1. In combination with the metal plates of a commutator, insulating removable cut-out segments of hard gummy woods.
2. The combination, with the metal plates 95 of a commutator, of the removable cut-out segments of lignum-vitæ.
3. In combination with the metal plates of a commutator, the insulating cut-out segment provided with transverse grooves in its wearing-surface.
4. In combination with the metal plate of a

commutator, the insulating cut-out segments provided with transverse grooves cut diagonally to the axis of the commutator.

5. The combination, with the metal plates of a commutator, of the removable cut-out segments provided with V-shaped grooves.

6. The combination, with the metal plates of a commutator, of the cut-out segments of insulating material tipped with refractory material at the end.

7. The combination, with the metal plates of a commutator, of insulating cut-out segments formed of wood and having the end grain presented for wear.

In testimony whereof I hereunto set my hand this 1st day of December, 1885.

THOMAS E. ADAMS.
